(57) **CLAIM**

The ornamental design for a rack with pegs, as shown and described.

DESCRIPTION

FIG. 1 is a perspective view of a rack with pegs showing a first embodiment of our new design;

FIG. 2 is a left side elevational view thereof, with a right side elevational view being a mirror image thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is an enlarged perspective view of a portion thereof; and,

FIG. 8 is a perspective view of a rack with pegs showing a second embodiment of our new design.

The view of FIG. 7 is shown fragmented and enlarged for clarity of illustration.

The portions shown in broken lines in FIGS. 1, 3, 4 and 8 are for illustrative purposes only and form no part of the claimed design.
